UNITED STATES PATENT OFFICE.

WILLIAM H. JAY, OF OTTAWA, ILLINOIS, ASSIGNOR OF TWO-FIFTHS TO
LEE O'NEIL BROWNE AND HERBERT C. WILEY, OF OTTAWA, ILLINOIS.

CARRIAGE-TOP.

No. 839,768.

Specification of Letters Patent.

Patented Dec. 25, 1906.

Application filed March 9, 1906. Serial No. 305,116.

To all whom it may concern:

Be it known that I, WILLIAM H. JAY, a citizen of the United States, residing at Ottawa, in the county of Lasalle and State of Illinois, have invented certain new and useful Improvements in Carriage-Tops, of which the following is a specification.

My invention relates to carriage-tops, and has for its object the production of a collapsible vehicle-seat cover upheld by a folding frame having component parts of special and particular construction and arrangement believed to enable the occupant of the seat to raise or lower the top with the minimum of labor and without passing the hands between the bows or outside of the curtains at the side.

I accomplish the objects set forth by fashioning and associating the parts as illustrated in the accompanying drawings, of which—

Figure 1 represents a sectional view of the frame and top raised. Fig. 2 is a sectional view with the frame and top inclined to the rear. Fig. 3 is a sectional view showing the top collapsed and the frame folded. Fig. 4 is a fragmentary back view of the seat and shows in partly sectional form the lifting-spring applied to the shorter member of the main brace. Fig. 5 represents a fragmentary side view showing the position of the lifting-spring when the top is raised.

Like letters are used to designate the same parts in all the views.

The letter A designates the body of the buggy, of which B marks the seat, and C and C' the side rails upon the side boards of the seat. The rail nearest the observer is broken away to disclose its fellow on the farther side.

40 The back of the seat is referred to by letter D.

The usual bows of the frame are lettered E, F, and G.

The horizontal bow-braces, which maintain the bows in their proper separated attitudes when the top is raised, are designated H, and they possess the customary downwardly-folding joints h h and an intermediate joint h', which is pivotally secured to the 50 bow F.

The main brace, which has its upper end pivotally connected with the above-mentioned joint h', is composed of the long member J and the short member j, coupled by the

knee-joint j', which, it will be observed, breaks forwardly, and not rearwardly, as is the case in every similar construction of which I have knowledge.

The cover of the top is referred to by the letter K, and the rear curtain by the letter L.

In some instances—and particularly with a heavy top having four or more bows, for example—it is desirable to provide assistance to the occupant in raising the whole. To render this assistance, I introduce the bracket M, secured to the back D of the seat and having the stem m. The shorter member j of the main brace is shown in Fig. 4 with the stem m passing through its lower end j². Attached to the stem is the lifting-spring N, and its outermost extremity has a hook n, engaging the shorter member j of the main brace. The spring is usually protected by the encircling bell n'. (Shown in the drawings in Figs. 4 and 5.)

75 The operation of my invention is the following: From Figs. 1, 2, and 3 it will be discerned that the main brace and all joints are inside the cover and bows—that is to say, any person desiring to bring the top from the 80 position of Fig. 1 into that delineated in Fig. 2 may directly grasp the main brace without passing the hands between the bows or outside the curtain. In Figs. 2 and 3 the reason for constructing the upper member J of the 85 main brace the longer will be noted. It is to permit the folding of the frame. The lengths of the two members J and j of the main brace are in such proportion one to the other as to allow for the folding of the frame. 90 It is also believed to be evident that the construction wherein the main brace breaks forwardly is more easily operated than one in which such brace breaks rearwardly, for the reason that the back of the rider is against 95 the back B of the seat, thus affording a base for a strong push in a forward direction, whereas no basis is present for a push to the rear.

When my invention is applied to heavy tops, as stated, the spring N, as shown in Fig. 5, is normally in an upright position, and when the frame is folded the member j of the main brace falls forwardly and bends the spring downwardly. The weight of the top may thus be taken up, and when it is desired to again raise the top the spring exerts its force to accomplish that purpose. A further office of the spring N when the cover is in its

raised position is to uphold the member j of the main brace when subjected to jars or jolts which might otherwise cause joint j' to break forwardly. The joint may give a little in consequence of such jolts; but the spring acts to quickly replace it.

Having thus described my invention and explained the nature of its operation, what I claim is—

- 10 In a carriage-top, the combination with the bows, of the bow-braces H pivotally connected with all of the bows and arranged upon the inside of the bows, the said bow-braces having joints occupying intermediate positions with respect to the said bows when the carriage-top has been raised, and the forwardly-inclined main braces having their upper ends pivotally connected with the said
- 15

bow-braces on the inside thereof whereby the said main braces are arranged diagonally inside of the said bows and bow-braces when the cover is raised and adapted to be reached from the seat without passing the hands between the bows, the said main braces each consisting of two straight members connected together by a forwardly-breaking joint, and both of said members adapted to assume horizontal positions when the top is lowered, substantially as described.

In testimony whereof I affix my signature in presence of two witnesses.

WILLIAM H. JAY.
